WINDOW CASE STRUCTURE

John P. Francis, 20 Boston St., Haverhill, Mass. 01830

Continuation-in-part of design application Ser. No. 13,387, Sept. 4, 1968, now Patent No. 216,103, dated Nov. 25, 1969. This application Nov. 3, 1969, Ser. No. 19,899

Term of patent 14 years

Int. Cl. D25—02

U.S. Cl. D13—1

FIG. 1 is a perspective view of a window case structure, embodying my new design,

FIG. 2 is a side elevation view thereof,

FIG. 3 is a perspective view of another form of the invention wherein a top cover is employed, and

FIG. 4 is a side elevation view thereof.

The window structure fragmentarily shown in broken lines in FIGS. 1 to 4 inclusive is included for illustrative purposes only.

This is a continuation-in-part of design application Ser. No. D. 13,387, filed Sept. 4, 1968, now design Patent No. D. 216,103.

I claim:

The ornamental design for a window case structure, substantially as shown and described.
